CONTINUOUS BLEACHING PROCESS

Judson H. Sanders, Wyoming, Ohio, assignor to
The Procter & Gamble Company, Cincinnati,
Ohio, a corporation of Ohio

Application January 24, 1947, Serial No. 723,989

7 Claims. (Cl. 260—427)

1

This invention relates to an improvement in continuous processes for bleaching caustic refined glyceride oils.

When glyceride oils such as cottonseed oil or soybean oil are commercially refined and bleached by batch methods, the customary steps include: 1(a) adding a dilute solution of caustic soda to an agitated refining kettle nearly full of the crude oil, the amount of the alkali being somewhat more than that required to neutralize the free fatty acids and to react with coloring matter and albuminous impurities that are present in the crude oil, 1(b) continuing the agitation while raising the temperature of the oil gradually until the refining "foots" begin to melt and to coalesce in visible masses, i. e. to "break," 1(c) discontinuing the heating and agitation and allowing the foots to settle out of the refined oil, and after an interval drawing off the refined oil; 2(a) permitting this oil to settle again for several hours to substantially remove remaining traces of foots, 2(b) filtering the settled oil through kieselguhr or other filtering medium to remove traces of moisture and dissolved soap; 3(a) adding to the thus clarified oil in an agitated bleach tank a color absorbing material such as fuller's earth or activated clay and agitating for a period of time at a slightly elevated temperature, 3(b) removing the bleaching earth from the oil by filtration.

For some years the vegetable oil refining industry has to a great extent been practicing a continuous refining process in which continuous mixing and heating during flow through a small tank has replaced the above steps 1(a) and 1(b), and centrifuging has replaced the gravity settling and decanting of step 1(c). The bleaching operation, steps 3(a) and 3(b), is still performed as a batch process by a major portion of the industry.

Continuous refining and centrifuging has not eliminated the necessity of further clarification of the oil before bleaching, such as is provided by steps 2(a) and 2(b), and these steps are still common practice prior to bleaching by batch methods. A continuous procedure which accomplishes most of the objectives of these steps 2(a) and 2(b) is continuous water washing followed by a second centrifuging. This, however, leaves the oil wet with dissolved and minutely dispersed

5 water containing traces of dissolved soap, which is detrimental to good bleaching as currently practiced. Hence when continuous water washing of refined oil followed by centrifuging is practiced, it is customary to follow this by drying the oil, usually under vacuum in order to avoid overheating, prior to bleaching—this being the normal practice whether the bleaching is to be by batch or by a continuous method. Upon drying the oil, the traces of soap which it contains are dehydrated, and after the bleaching the dehydrated soap is filtered out along with the spent bleaching earth.

10 The present invention arises from the discovery that unexpected and advantageous results, in the form of lighter bleached oil colors, are obtained by rearranging the steps of the continuous water washing and bleaching process, to accomplish the absorption of coloring matter by the bleaching clay before instead of after the oil is dried.

15 It is my belief that the dehydration of the traces of soap contained in water washed oil in prior art processes results in an extraction of coloring matter by the oil from the soap, and that the lower bleach colors obtained by my process are largely the result of either preventing this color extraction or delaying it until bleaching clay is dispersed throughout the oil in a position to absorb the color released by the soap.

20 Objects of the present invention are to render unnecessary the step of drying before bleaching, to avoid the extraction of coloring matter by the oil from traces of soap in the oil, to improve the color removal of the bleaching operation, and to provide a practical and economical continuous washing and bleaching process.

25 The accompanying flow chart indicates the order of the steps of the process. The solid lines with arrows show the preferred sequence, and the dotted lines indicate two independent optional alternatives, (A) and (B).

30 The following is an example of the practice of my invention using in this instance freshly caustic-refined cottonseed oil. The oil is continuously supplied from the foots removing centrifuges, 35 in this case at a temperature in the neighborhood of 130° F., and is continuously mixed and agitated for about a minute or more in a closed 40 chamber with a continuous stream of water

amounting to about 15 per cent more or less of the weight of oil, and the mixture is then continuously fed through another centrifuge to remove the aqueous phase containing dissolved soap and other impurities. The wet oil issuing from this second centrifuge is continuously admixed with a continuously proportioned supply of bleaching clay, preferably supplied in the form of a slurry of clay in previously refined and bleached oil, and this mixture is passed through a zone of vigorous mechanical agitation, requiring some minutes for this passage, and thence through a suitable heater where its temperature is raised to about 175° F. From this heater the wet oil-earth mixture passes to a flash tank which is maintained under a reduced pressure which should be below the vapor pressure of the water in the oil at the temperature of the flash-dried oil. In this flash tank the water contained in the mixture vaporizes and is drawn off through a vapor exit leading from the top of the vaporizing chamber. The dried oil-earth mixture, or slurry, now at a temperature reduced to about 160° F. as a result of the evaporative cooling, is then sent to a suitable filtering apparatus for removal of the bleaching earth. A rotary filter may be used, or an alternating pair of filter presses of a conventional design. It may be desirable to precool the oil before filtration in order to avoid any deleterious oxidation upon its contact with the atmosphere.

In the practice of my process, the oil during its contact with the bleaching clay may have temperatures hitherto acceptable for bleaching by the conventional practice above referred to, say from 120° F. to 220° F., and the time of contact should be sufficient to accomplish effective color removal—at least one minute under conditions of good agitation. The oil temperature at the beginning of its flash drying should preferably be between 140° F. and 220° F.

The process may be varied in a number of respects without departing from the spirit or scope of the invention. For example, the heating of the wet oil prior to flash drying may be done before the addition of bleaching clay instead of after. The filtration of the bleached oil, to remove the bleaching clay and traces of soap together with the coloring matter absorbed by the clay and the soap, may even be done before the flash drying step—although this brings about obvious filtration difficulties if enough moisture is present to make the filter cake slimy.

The process is applicable to all caustic refined glyceride fats and oils, including animal fats such as lard and tallow, vegetable fats and oils such as palm oil, coconut oil, cottonseed oil, peanut oil, and soybean oil, and marine oils such as whale oil, herring oil, and sardine oil. Its advantage in producing lighter colored bleached oil is outstanding in the case of oils having a high ratio of coloring matter in the refining foots as compared with the amount of color in the refined oil. Thus the process is particularly advantageous when employed in the processing of cottonseed oil. The process is particularly appropriate as applied to freshly refined oil, but will find application also to settled refined oils which still contain traces of refining foots.

The following table, based upon the processing of three identical portions of a lot of freshly refined oil, gives a comparison of the steps and results characteristic of the present process (column a), as compared with a prior art process in

which the water washed oil is vacuum dried before bleaching (column b), and also compares these two procedures with batch clarification and bleaching (column c).

	(1)	Continuously refine crude cottonseed oil, and centrifuge.		
10	(2)	Water wash 2 min. at 140° F. with 20% by weight of water, centrifuge, and heat to 180° F.	Settle 6 hrs. and decant, filter through guhr (Lovibond color 35Y 6.5R)	
15	(3)	Bleach 15 min. with 3% Pike's Peak fuller's earth.	Vacuum dry at 5 mm. Hg pressure (Lovibond color 50Y 8.0R).	Bleach 15 min. at 180° F. with 3% Pike's Peak fuller's earth.
20	(4)	Vacuum dry at 5 mm. Hg pressure.	Bleach 15 min. at 180° F. with 3% Pike's Peak fuller's earth.	
25	(5)	Filter	Filter	Filter
		Lovibond color 20Y 2.5R.	Lovibond color 20Y 2.9R.	Lovibond color 20Y 2.6R.
		(a)	(b)	(c)

Thus the process of the present invention produces bleached oil of materially lighter color than the prior continuous process, and fully as light as the slower batch process.

Having thus described my invention, what I claim and desire to secure by Letters Patent is:

1. The improvement in the continuous process of bleaching caustic refined, water washed, and centrifuged glyceride oil which comprises effectively contacting the washed and centrifuged oil, containing residual dissolved and entrained moisture, with bleaching clay for at least one minute to cause the absorption of coloring matter from the oil by the clay, delaying the removal of the moisture contained in the oil-clay mixture until effective color absorption has occurred, and then removing said moisture by vacuum drying and said clay by filtration from said oil.
2. The process of claim 1 in which the vacuum drying of the decolorized oil precedes the filtration to remove the clay.
3. The process of claim 1 in which the filtration to remove the clay from the decolorized oil precedes the vacuum drying of the oil.
4. The continuous process of bleaching caustic refined, water washed, and centrifuged glyceride oils which comprises: continuously and intimately admixing a flowing stream of the washed and centrifuged and undried oil with a minor proportion of bleaching clay; passing this mixture through a zone of vigorous mechanical agitation while retaining the moisture in the mixture until effective color removal has occurred; continuously introducing the wet oil-clay slurry, heated to a temperature in the range 140° F. to 220° F., into an enclosed drying chamber which is maintained, by the continuous withdrawal of water vapor, at a pressure below the vapor pressure of the water in the oil at the temperature of the oil after the evaporative cooling which occurs in said chamber; and continuously filtering the bleaching clay from the resulting vacuum dried oil.
5. In the continuous refining, water washing, and bleaching of glyceride oils the steps which comprise bleaching undried water washed refined oil with bleaching clay in the presence of residual moisture, followed by the steps, in different order

of removing said moisture by vacuum drying and said clay by filtration from the bleached oil.

6. The process of claim 1 in which the caustic refined glyceride oil is cottonseed oil.

7. The process of claim 4 in which the caustic refined glyceride oil is cottonseed oil.
